(57) **CLAIM**

The ornamental design for a grommet, as shown and described.

DESCRIPTION

FIG. 1 is a front view of a grommet showing our new design, a rear view being identical to the front view;

FIG. 2 is a plan view thereof;

FIG. 3 is a right side view thereof, a left side view being identical to the right side view;

FIG. 4 is a bottom view thereof;

FIG. 5 is a cross-sectional view thereof taken along line 5-5 in FIG. 2;

FIG. 6 is a cross-sectional view thereof taken along line 6-6 in FIG. 2;

FIG. 7 is a front view of an axial body of the grommet shown separated for ease of illustration with a rear view being identical to the front view;

FIG. 8 is a plan view thereof;

FIG. 9 is a right side view thereof, a left side view being identical to the right side view;

FIG. 10 is a bottom view thereof;

FIG. 11 is a cross-sectional view thereof along line 11-11 in FIG. 8;

FIG. 12 is a cross-sectional view thereof along line 12-12 in FIG. 8;

FIG. 13 is a front view of a main body of the grommet shown separated for ease of illustration with a rear view being identical to the front view;

FIG. 14 is a plan view thereof;

FIG. 15 is a right side view thereof, a left side view being identical to the right side view;

FIG. 16 is a bottom view thereof;

FIG. 17 is a cross-sectional view thereof along line 17-17 in FIG. 14;

FIG. 18 is a cross-sectional view thereof along line 18-18 in FIG. 7;

FIG. 19 is a cross-sectional view thereof along line 19-19 in FIG. 7; and,

FIG. 20 is a cross-sectional view thereof along line 20-20 in FIG. 10.
